Roger Vivier, Mougins, France, assignor to Christian Dior,
Paris, France, a limited liability company of France

Application March 13, 1959, Serial No. 54,973

Claims priority, application France January 14, 1959

Term of patent 7 years

(Cl. D7—5)

Fig. 1

Fig. 2

Fig. 4

Fig. 3

Fig. 5

Fig. 1 is a side elevational view of a heel for ladies' shoes showing my new design;

Fig. 2 is a top plan view of the heel shown in Fig. 1;

Fig. 3 is a rear view;

Fig. 4 is a bottom plan view; and

Fig. 5 is a front elevational view thereof.

I claim:

The ornamental design for a heel for ladies' shoes, substantially as shown.
